UNITED STATES PATENT OFFICE

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

FIRE-EXTINGUISHING APPARATUS

Application filed December 24, 1927. Serial No. 242,406.

This invention relates to improvements in fire extinguisher apparatus and particularly in that class of apparatus which utilizes as the active medium a foam which spreads over the burning surfaces and smothers the fire.

This foam is frequently generated by the addition of water to a suitable chemical compound, and the principal object of the present invention is to provide novel apparatus automatically operative to admit water in suitable measured quantities to a supply of the foam-forming substance when circumstances require the production of the foam at a given point.

More specifically the invention contemplates the provision of means actuated by the development of excessive temperature at predetermined points for initiating a flow of water into a suitable vessel or accumulator containing a specified quantity or charge of the foam-forming substance, for maintaining said flow until the foam-forming substance has become exhausted, and for then interrupting the flow.

Another object of the invention is to provide means whereby the apparatus automatically restores itself to operative condition following resetting of the actuating element or elements, as hereinafter more specifically set forth.

The invention further resides in certain novel structural features and details including novel forms of valve constituting elements of the combination.

In the attached drawings:

Figs. 1 and 2 are respectively side and front elevational views, more or less diagrammatic, illustrating apparatus made in accordance with my invention;

Fig. 3 is an elevational view of the accumulator;

Fig. 4 is an elevational view partly in section illustrating the thermostatic release element and associated valve;

Fig. 5 is a front elevation of the parts shown in Fig. 4; and

Fig. 6 is a sectional enlargement of one of the control valves.

Referring especially to Figs. 1, 2 and 3 of the drawings, the apparatus forming the

subject of my invention comprises a foam accumulator 1 with the bottom of which communicates a pipe 2 which in the present instance extends from a suitable source of water supply such, for example, as a water main.

The accumulator 1 is adapted to hold a predetermined quantity of a substance reactive with water to generate the foam constituting the active fire-extinguishing agent. The said substance may be admitted to the accumulator through a normally closed port 4 at the top, and the foam generated when the water is admitted is permitted to escape through an outlet 5, also at the top of the vessel.

The pipe 2 is normally closed by a valve 10 established in a casing 11 which includes an upper section 12 divided interiorly by a flexible diaphragm 13 into upper and lower chambers 14 and 15 respectively. The stem 16 of the valve 10 projects upwardly into the chamber 15 and carries at the top a concaved plunger 17 which bears against the underside of the diaphragm 13. A spring 18 exerts a pressure tending to elevate the valve 10 from its seat. The chamber 15 is connected through a pipe 19 with a drain pipe 20, while the chamber 14 is directly connected through a pipe 21 with the lower chamber 22 of a valve casing 23.

This chamber 22 of the casing 23 is connected with the water-supply pipe 2 through a branch 24 and a connecting pipe 25. The pipe 25 contains a valve 26 and communicates with the chamber 22 through an opening 27 which is controlled by a stem 28 projecting therethrough from the interior of the chamber. The stem 28 is carried by plunger 29 normally resiliently held against one end of a cylinder 30 by a spring 31. Access may be had to the cylinder through a threaded plug 32 which closes the outer end of the cylinder. The effective area of the port 27 is determined by the size of the stem 28, and its more or less close fit in the opening.

A port 33 in the top of the chamber 22 is normally closed by a valve 34. This valve is engaged by an element 35 extending up

wardly in the casing and held in contact with the underside of a flexible diaphragm 36,— which divides the upper part of the casing 23 to form within the latter an intermediate chamber 37 and an upper chamber 38,—by a spring 39. The connection between the valve 34 and element 35 is a universal one insuring correct seating of the valve.

The chamber 37 is connected through a pipe 45, see Fig. 2, with a reservoir in the form in the present instance of a pair of upright cylinders 46 connected together and with the pipe 45 at the bottom, and being connected also at the top through a pipe 47 having associated therewith a suitable float-valve controlled air vent 48.

The chamber 38 of the casing 23 is connected through a pipe 52 with a chamber 53 in a valve casing 54, the pipe 52 having a pressure gage 49 connected therewith through a valve pipe 50. As shown in Fig. 4, this chamber has extending therefrom a cylindrical extension 55 in which operates a plunger valve 56. This valve normally closes the inner end of the cylinder 55 and separates it from the chamber 53. The valve 56 carries a stem 57 which projects into and more or less obstructs a port 58 in the chamber 53, this port communicating with the upper end of the pipe 24 extending from the supply pipe 2. The relative cross-sectional sizes of the port 58 and the stem 57 determine the effective opening of the port. The outer face of the valve 56 is so formed as to completely close the port 58 when the valve 56 is shifted as hereinafter set forth. From the top of the chamber 53 a pipe 59 containing a check valve 60 extends to one or more sprinkler heads 61 adapted to open under excessive temperatures 43 and located as desired. The cylindrical chamber 55 also has a port 62 which communicates through a pipe 63 with the drain pipe 20. A spring 64 in the chamber 55 tends to force the valve 56 from its normal seat closing the cylinder and the valve plunger is so designed that when the valve is unseated the chambers 53 and 55 are immediately in communication.

The valve 56 is attached to a stem 65 which extends through the rear of the casing 54 and into the interior of a casing 66 rigidly connected with the casing 54 by arms 67. The casing 66 has a port 66a which is connected through a pipe 68 with the drain pipe 20 and which communicates through a port 69 with a chamber 70 in the casing. This chamber holds a valve element 71 adapted to close the port 69 but normally retained in a retracted position as shown by the stem 65 which loosely engages the valve. When the stem 65 is withdrawn, as hereinafter described, a spring 72 forces the valve forwardly against its seat closing the port 69. Access to the chamber 70 and to the valve is had through a threaded plug 73 closing the outer end of the chamber. The chamber 70 is also connected through a

pipe 74 with the pipe 45, see Fig. 2, and with a pressure gauge 75.

Intermediate the casings 54 and 66 the stem 65 is engaged by a U-lever 80 pivotally suspended at 81 between arms 82—82 of a bracket 83 secured to the casing 54. The connection between the lever 80 and the stem 65 is an operating one, in which trunnions 84—84 on the lever arms project into an annular recess 85 in the stem.

Pivotal mounted at 86, between arms 87—87, on the bracket 83 is a second lever 88. This lever has a part 89 which projects between the arms of the lever 80 and at the outer end of this part 89 are oppositely projecting lugs or arms 90 having sufficient span to engage the arms of the lever 80. Similar lugs 91 are provided on a projecting part 92 of the lever at the opposite side of the lever 80, so that the lever 80 in effect is confined between these two sets of lugs 90—90 and 91—91 on the lever 88. A bolt 93 passes transversely through the upper end of the lever 88 and carries a stirrup 94 whose arms 95 lie against the opposite faces of the lever 80 and which is adapted to hook over a projection 96 on a lever 97 forming a part of an electric release hereinafter described. The bolt 93 also carries outwardly of the stirrup 94 a pair of weight elements 98 whose function will be described hereinafter.

The electric release device of which the lever 97 constitutes a part may consist of suitable electrically releasable means contained in a housing 99 secured to the bracket 83, see Fig. 4, for retaining the lever 97 in the elevated position, as shown, against the pressure of the weights 98 and associated suspended parts, which tend to pull the lever downwardly about its pivot 100 on the housing 99. Such a device is illustrated for example in U. S. Patent No. 1,312,895, dated August 12, 1919. The said device further comprises thermosensitive means 104 operative at predetermined temperatures to close the electric circuit of the aforesaid electrical means to thereby release the lever 97 and the parts suspended therefrom. A thermosensitive switch of this character is shown for example in U. S. Patent No. 1,274,248, dated July 30, 1918.

The apparatus further includes in the illustrated embodiment, a suitable alarm device 101, located in the pipe 2 intermediate the valve 10 and the accumulator and actuated by water pressure in this pipe to close an electric circuit 102 including a suitable electric signal. This part of the pipe 2 also contains a drain 103 of the type including a ball float which permits escape of relatively small quantities of water leaking past the valve 10 and functioning to close the drain port when a large volume of water is admitted by opening of the valve.

The apparatus is prepared for operation

by placing in the accumulator tank a predetermined quantity of the foam-forming substance, and by elevating the lever 97 of the release device and with it the lever 88. To close the valve 56, the lever 80 is provided with a handle 79 and through the lever 80 the stem 65 may be shifted rearwardly to an extent bringing the valve 56 to its seat, as shown. The chamber 53 being now connected through the port 58 with the water main, water fills the chamber and the main pressure holds the valve 56 to its seat against the pressures of the springs 64 and 72. Water also fills the pipes 59 and 52 and the chamber 38 in the valve casing 23, and the main pressure acting on the diaphragm 36 and through the element 35 retains the valve 34 on its seat, closing the port 33. The chamber 22, by reason of its connection with the supply pipe 2 through the pipes 24 and 25, also is filled with water, but the differential areas of the port 33 and diaphragm 36 prevent the valve from opening. Water is thus excluded from the pipe 45 and cylinders 46 and any water that may previously have occupied the cylinders is permitted to drain through the pipes 74 into the chamber 70 of the casing 66. The valve 71 in this chamber is held in the retracted position by the stem 65 and the port 69 is therefore open to permit any water entering the chamber 70 to pass through the pipe 68 to the drain.

The chamber 14 of the casing 11 is also filled with water, the main pressure acting through the diaphragm 13 to seat the valve 10 against the opposing main pressure acting on the relatively small area of the underside of the valve. Water is thus excluded from the accumulator, such small leakage as may occur past the valve 10 being drained off through the drain 103 provided for that purpose.

Assuming now that the temperature conditions are such as to actuate the thermostat 45 to release the lever 97. This in turn releases the stirrup 94 and the weights 98 cause a rotational movement of the lever 88 bringing the lugs 91 into contact with the lever 80 with sufficient force to open the valve 56 through the medium of the stem 65. Shifting the stem in this manner results in bringing the valve 56 into position closing the port 58 and also opens the chamber 53 to the drain through the chamber 55 and port 62. The valve 71 is also permitted to move by action of the spring 72 into position closing the port 69.

Closing the port 58 and draining the chamber 53 relieves the pressure on diaphragm 36 and permits the spring 39 to elevate the element 35 and to allow the valve 34 to open. Water now flows through the pipe 45 to the cylinders 46 and the rate of this flow is determined, as described, by the stem 28 in the port 27. It will be noted that the connection 65 of the cylinders 46 with the drain through the

pipe 74 has been closed by the previous closing of the valve 71.

With the opening of the valve 34, pressure in the chamber 14 of the casing 11 is relieved and the water pressure under the valve 10 together with the spring 18 lifts the said valve from its seat and permits water to flow through the pipe 2 to the accumulator. This flow continues until the cylinders 46 become full, at which time the pressure in the chambers 22 and 14 is restored and the valve 10 again forced to its seat. Obviously, the period during which the valve 10 remains open may be regulated as desired by adjusting the effective size of the port 27 in conjunction with the capacity of the cylinders 46. This period of flow to the accumulator is calculated to give in the latter a supply of water proportionate to the amount of the foam-forming substance in the accumulator.

As set forth above, return of the various operating parts to their original positions results automatically in a flow of water in the apparatus such that the original condition is obtained.

The apparatus is also actuatable through the medium of a sprinkler head of usual design, such as that shown at 61. Opening of this head under extraordinary temperature conditions results in relief of pressure in the chamber 53 and the unseating of the valve 56 by action of the spring 64. The consequent operation is substantially the same as previously described.

It will be apparent that the apparatus described is subject to modification without departure from the invention as defined by the appended claims.

I claim:

1. In fire-control apparatus, the combination with a fluid-supply duct, of a valve controlling said duct, fluid pressure means for retaining the valve normally closed, thermally actuated means for relieving the pressure to permit the valve to open, and means automatically operative to re-apply said pressure after a predetermined interval to close the valve.

2. In fire-control apparatus, the combination with a fluid-supply duct, of a valve controlling said duct, means utilizing the fluid-supply pressure for retaining the valve normally closed, thermally-actuated means for relieving the pressure on the valve to permit the valve to open, and means automatically operative to restore the pressure to re-seat the valve after a predetermined interval.

3. In fire-control apparatus, the combination with a fluid-supply duct, of a valve controlling said duct, means utilizing the fluid-supply pressure for retaining the valve normally closed, said means including a pressure chamber connected with the source of fluid supply and with a second chamber, a valve controlling the connection between said

chambers, means for retaining the last named valve normally closed, thermally actuated means for releasing said retaining means to permit the last-named valve to open, thereby relieving the fluid-pressure on the first named valve and permitting said first-named valve to open, and said fluid-pressure being restored and the first named valve re-seated when the said second chamber becomes filled with fluid from the source of supply.

10 4. In fire-control apparatus, the combination with a fluid-supply duct, of a valve in said duct intermediate the said source and the chamber, means utilizing the fluid-supply pressure for normally retaining the valve closed, thermally-actuated means for relieving said pressure with respect to the valve to permit the latter to open, and means automatically operative to re-apply said pressure to close the valve.

15 5. In a fluid supply system, the combination with a duct extending from a source of fluid supply, of a valve in the duct, means for closing and for normally retaining the valve closed including a pressure chamber connected with said source of supply, a normally empty chamber, a passage connecting said chambers, a valve in said passage, means normally retaining said last-named valve closed, 20 thermally-actuated means for releasing said retaining means to permit the last-named valve to open, thereby relieving the pressure in the pressure chamber and permitting the first-named valve to open and to remain open until the said normally empty chamber is 25 filled and the pressure thereby restored in the pressure chamber.

30 6. In a fluid supply system, the combination with a source of fluid supply, of a duct 40 extending therefrom, a valve in the duct, means including a pressure chamber connected with the said source of supply for closing said valve and for normally retaining it closed, a normally empty chamber, a passage 45 connecting said chambers, a valve in said passage, means normally retaining said last-named valve closed, thermally-actuated means for releasing said retaining means to permit the last-named valve to open, and 50 means for restricting the flow from the source of supply into said pressure chamber whereby when the last-named valve is opened the pressure in the pressure chamber is relieved to thereby permit the first-named valve to 55 open and to remain open for a predetermined time interval until the said normally empty chamber is filled and the pressure thereby restored in the pressure chamber.

60 7. In a fluid supply system, the combination with a source of fluid supply, of a duct extending from said source, a valve in the duct, means for utilizing the fluid pressure in said duct for closing said valve and for normally retaining said valve closed, means 65 for relieving the valve-closing pressure and

for automatically re-applying said pressure after a predetermined time interval, a valve controlling said latter means, means for utilizing the pressure in said duct for normally retaining the last-named valve closed, and thermally-actuated means for relieving the closing pressure on said latter valve to permit the first-mentioned valve to open.

70 8. In a fluid supply system, the combination with a source of fluid supply, of a duct 75 extending from said source, a valve in the duct, means for utilizing the pressure in said duct for closing said valve and for normally retaining the valve in closed position, means for relieving the valve-closing pressure to 80 permit the valve to open and for re-applying said pressure to close the valve after a predetermined time interval, said latter means including a chamber connected with the source of supply, and a valve controlling said connection, means for utilizing the pressure in said duct to close the latter valve and to retain it normally in closed position, and a thermally-actuated valve structure including 85 a valve adapted when closed to maintain the said valve-closing pressure, and when open to relieve the said pressure, and a second valve adapted when open to drain the said chamber, and when closed to prevent said drainage.

90 9. In a fluid supply system, the combination with a source of fluid supply, of a duct 95 extending from said source, a valve in said duct, means for normally retaining said valve closed including a second valve, means 100 including a pressure chamber connected with the source of supply for normally retaining said second valve closed, an exhaust port in said chamber, a valve normally closing said exhaust port and adapted in an alternative position to close the connection between the said pressure chamber and the source of supply, and thermally-actuated means mechanically associated with said valve for shifting the latter from the normal position closing 105 said exhaust port to the said alternative position to thereby relieve the pressure on said second valve to permit said valve to open and thereby to permit the opening of said first valve.

110 10. In a fluid supply system, the combination with a source of fluid supply, of a duct 115 extending from said source, a valve in said duct, means for normally retaining said valve closed including a second valve, means 120 including a pressure chamber connected with the source of supply for normally retaining said second valve closed, an exhaust port in said chamber, a third valve normally closing said exhaust port and adapted in an alternative 125 position to close the connection between the said pressure chamber and the source of supply, thermally-actuated means for shifting said third valve from the normal position closing said exhaust port to the said 130

alternative position to thereby relieve the pressure on said second valve to permit said second valve to open and thereby to permit the opening of said first valve, means including a chamber having a connection with the source of supply controlled by said second valve for re-closing said first valve after a predetermined time interval, an exhaust port in said latter chamber, a normally open valve adapted to control said exhaust, and means operatively connecting the normally open valve with said thermally-actuated means whereby the latter in shifting the third valve in the said pressure chamber to open the exhaust thereof closes the normally open valve of said other chamber.
